US00D949626S

(12) **United States Design Patent** (10) **Patent No.:** **US D949,626 S**
(45) **Date of Patent:** **** Apr. 26, 2022**

(54) **BEVERAGE CONTAINER LID**

(71) Applicant: **Pacific Market International, LLC**,
Seattle, WA (US)
(72) Inventor: **Mercedita Andrew**, Seattle, WA (US)
(73) Assignee: **Pacific Market International, LLC**,
Seattle, WA (US)
(**) Term: **15 Years**
(21) Appl. No.: **29/719,769**
(22) Filed: **Jan. 7, 2020**
(51) LOC (13) Cl. **07-01**
(52) U.S. Cl. **D7/392.1; D7/396.2**

(57) **CLAIM**

The ornamental design for a beverage container lid, as shown and described.

DESCRIPTION

FIG. 1 is a top perspective view of a beverage container lid showing my new design.

FIG. 2 is a bottom perspective view thereof.

FIG. 3 is a front elevational view thereof.

FIG. 4 is a left side elevational view thereof.

FIG. 5 is a right side elevational view thereof.

FIG. 6 is a rear elevational view thereof.

FIG. 7 is a top plan view thereof; and,

FIG. 8 is a bottom plan view thereof.

The broken lines depict environment and form no part of the claimed design.

The dot-dash broken lines depict a boundary line within which the portions of the beverage container lid form no part of the claimed design.

1 Claim, 7 Drawing Sheets
